CLAIM

The ornamental design for a gaseous diluter, as shown and described.

DESCRIPTION

FIG. 1 is a lower front and right side perspective view of an embodiment of a gaseous diluter in accordance with our new design.

FIG. 2 is a front side view of the gaseous diluter of FIG. 1. FIG. 3 is a back side view of the gaseous diluter of FIG. 1. FIG. 4 is a top side view of the gaseous diluter of FIG. 1. FIG. 5 is a bottom side view of the gaseous diluter of FIG. 1.

FIG. 6 is a right end view of the gaseous diluter of FIG. 1. FIG. 7 is a left end view of the gaseous diluter of FIG. 1. FIG. 8 is a perspective view of another embodiment of a gaseous diluter in accordance with our new design.

FIG. 9 is a front side view of the gaseous diluter of FIG. 8. FIG. 10 is a back side view of the gaseous diluter of FIG. 8. FIG. 11 is a top side view of the gaseous diluter of FIG. 8. FIG. 12 is a bottom side view of the gaseous diluter of FIG. 8.

FIG. 13 is a right end view of the gaseous diluter of FIG. 8; and, FIG. 14 is a left end view of the gaseous diluter of FIG. 8.
